UNITED STATES PATENT OFFICE

GEORGE R. WOOD, OF TORONTO, ONTARIO, CANADA, ASSIGNOR TO INTERNATIONAL BUSINESS MACHINES CORPORATION, OF NEW YORK, N. Y., A CORPORATION OF NEW YORK

TIME RECORDER

Application filed November 17, 1927, Serial No. 233,978, and in Canada September 15, 1927.

My invention relates to workmen's time recorders of the dial type in which the time sheet is carried by a cylindrical drum or platen and a time controlled printing carriage is adapted to move intermittently in a longitudinal direction across the time sheet and print the workmen's time as they come and go, in columns representing the working periods into which each day is divided, the actual printing movement of the carriage into contact with the time sheet being effected by each workman when he "punches" his number on the dial.

The divisions of the time sheet are varied to meet different requirements. The periods into which each work day is divided are in most instances "Morning in", "Morning out", "Noon in", "Noon out", "Extra in", "Extra out" so that each workmen's time at the commencement of the day's work is recorded in the "Morning in" column of that particular day, and when he stops work at mid-day the time is recorded in the "Morning out" column and so on, the overtime records appearing in the "Extra in" and "Extra out" column.

In recording machines of this type it is vitally important that the machine print a time record which is accurate to the minute.

Consequently the various mechanisms of which it is composed must be so constructed and arranged and so synchronized that each is capable of performing its respective function at the precise time it is required. It is also imperative that the operative relationship or relative setting of the parts be not disturbed during the operation of the recorder, otherwise a true record cannot be obtained. This is particularly true in respect of the escapement mechanism for controlling the intermittent movement of the carriage for this mechanism synchronizes the tabulating or intermittent movement of the carriage with the time element, and when it is disturbed the printed record on the time sheet is entirely wrong.

Owing to these conditions considerable difficulty has and still is being experienced with time recorders of this type, it being possible in the various recorders of this type heretofore used for the timekeeper or indi-

vidual in charge of the recorder to unwittingly make a P. M. setting for morning requirements instead of an A. M. setting in which case the error is usually not discovered until the confused and almost unreadable record of the time sheet is noticed. Then again the relationship between the time element and carriage was frequently disturbed during the normal operation of the machine causing further confused readings on the time sheet. This and many other minor troubles have been a source of constant trouble and expense and have so confused the pay sheets that heavy annual losses to employers have been the result.

The present invention seeks to overcome these difficulties by providing a time recorder having the following salient features:

(a) A time controlled carriage whose movement intermittently in a longitudinal direction along the time sheet is so controlled by the time element that it is impossible to disturb the columnar relationship of the carriage to the time sheet during the normal operation of the machine in so far as the work periods of each day are concerned. That is to say, if the carriage is opposite the "Morning in" column of say Wednesday in a weekly recorder it cannot, under normal conditions be moved to record in any other column than "Morning in" even though the carriage may be shifted manually to other days of the week. For abnormal conditions such as for instance when a workman has extended a work period beyond the allotted time and the carriage has been shifted for the next period special mechanism is provided to move the carriage back to record the stopping time in the preceding period but this is only a temporary shift and the carriage automatically assumes its correct columnar position when the operation is completed.

(b) A general construction and arrangement of parts which permits of easy assembly and repair work and makes it possible to vary the capacity of the recorder. That is to say, by a few minor replacements the capacity of a recorder may be increased from 50 employees to 100 or 100

150 as desired, or in like manner the capacity of the machine may be reduced.

In the past it has been necessary to construct three separate and distinct sizes of machine to take care of these different capacities.

(c) Carriage suspension means movable vertically in unison with the carriage, which ensures a uniform distribution of stresses and strains resulting from the manual dial "punching" operation, and which may be readily adjusted to obtain a uniform printing pressure of the type wheels throughout the length of the time sheet.

15 Other features will appear as the description progresses.

Referring to the accompanying drawings in which similar reference characters in the different views indicate the same parts:

20 Fig. 1 is a part side elevation and part longitudinal sectional view of a workman's time recorder constructed according to my invention;

Fig. 2 is a plan view thereof, drawn to a larger scale, of the time recording mechanism proper;

25 Figs. 3 and 4 are vertical sectional views taken on lines 3—3 and 4—4 respectively, of Fig. 2;

Fig. 5 is a sectional view taken on line 5—5 of Fig. 2 and illustrating the carriage;

Fig. 6 is a detail fragmentary view illustrating the rack and pinion suspension for the carriage;

30 Fig. 7 is a sectional view taken on line 7—7 of Fig. 8;

Fig. 8 is a plan view of the escapement mechanism for the carriage;

35 Figs. 9, 10 and 11 are diagrammatic views illustrating the tapes for moving the carriage;

Fig. 12 is a detail fragmentary plan view of the spring barrel and associated parts for inducing travel of the carriage in the normal direction, and,

40 Fig. 13 is a detail view of the carriage escapement wheel.

In the illustrated embodiment of the invention the recording mechanism is contained 50 within a cabinet 2 having the usual fixed dial 3 on the front thereof bearing the workmen's identifying numbers, and a manually operable lever 4 by which each workman is able to rotate the drum or platen to position in 55 which his time will be printed on the time sheet in longitudinal alignment with his allotted number, the time sheet bearing numbers corresponding with those on the dial. These dial numbers serve as visible guides 60 in the punching or recording operation, the workman in punching his time simply moving the lever 4 around the dial, on its central axis until the free end of the lever comes opposite his number, and then pressing the lever 65 inwardly towards the dial a sufficient distance

70 to cause the type wheels hereinafter referred to engage the time sheet, a circumferential series of spaced guiding openings 5 being formed in the dial opposite the numbers thereon for the purpose of receiving and guiding pin 6 on the lever during this operation.

75 The main supporting frame of the machine consists of unitary front and rear end frames 7 and 8 vertically disposed within the cabinet adjacent the front and rear walls thereof and fixed to the base of the cabinet at their lower ends as at 9, and horizontally disposed truss rods, 10, 11, 12, 13 and 14 extending between the end frames and having their ends mounted therein. The rod 14 braces the end frames at their extreme uppermost points while the other rods are arranged in pairs located above and below the drum platen and spaced equidistantly therefrom.

80 To facilitate assembly, adjustments, and repair work these truss rods 10, 11, 12 and 13 are simply passed through openings in the end frames and are secured therein by set screws 15, their front ends being extended through the front wall of the cabinet and carrying the dial 3, and the various other mechanisms are so constructed and arranged that in most instances they may be assembled on the end frames before the latter are placed in the cabinet.

85 The drum platen, indicated at 16, is of usual construction and is keyed upon a horizontal hollow shaft 17, which is journaled in bearings 18 and 19 on the end frames, the front end of the shaft being extended through the front cabinet wall and having the bracket 20, which hingedly carries lever 4, keyed thereon. The size of the platen will vary according to the capacity of the recorder. The end frames are consequently designed 90 to permit the location of the platen shaft therein in three different positions indicated at A, B and C in Fig. 4, the shaft being located in the first mentioned position for the usual small size platen having a capacity to take care of 50 workmen, or in the second position when the machine has a capacity for 100 workmen, or in the third position when the machine is to take care of 150 workmen, these being the usual sizes in which recorders of this type are constructed. This arrangement makes it possible to readily change the capacity of the machine with minimum disturbance and replacement of the parts and the cost of manufacture is consequently greatly reduced. In fact the construction and arrangement of parts throughout the machine has been developed with this desideratum in view so that the various parts common to all three types may be made in large quantities instead of having to be made in different sizes as has been the case in the past.

and 23, respectively, rotatively connected to the minute shaft 24 of the clock movement 25, and inking ribbon 26, are supported above the platen in a time-controlled carriage 27.

- 5 This carriage automatically moves intermittently along the time sheet transversely to the day columns thereon and its intermittent travel is synchronized with the clock movement through an escapement mechanism 10 hereinafter referred to. For details of the connection between the time wheels and printing wheels reference may be had to the Patent to R. Dey, No. 795,204, dated July 18, 1905.

- 15 The carriage consists of a sleeve 28 slidable longitudinally along a horizontally disposed suspension rod 29, end frames 30 and 31 rigidly and detachably secured at their upper ends upon the sleeve between collars 32 and 20 nuts 33, and an intermediate frame 33a mounted between the end frames adjacent their lower ends and carrying the ribbon in close proximity to the platen. These frame members are disposed transversely to and are 25 located between the truss rods 10 and 11, and the frame 31 has lateral extensions 31a presenting straight vertical bearing faces 31b which bear against these rods and thereby prevent lateral displacement of the carriage adjacent the printing point.

- 30 Automatic travel of the carriage in the normal direction is induced by a spring barrel 34 through a metal tape 35 which passes over intermediate pulleys 36 and 37 and is 35 connected to a laterally projecting bracket 38 adjustable on sleeve 28.

- The spring barrel contains a spiral spring 40 (see Fig. 12) which is connected at one 40 end to the circumferential wall of the barrel and at its opposite end to the stationary part 41 of a two part shaft, the other shaft part being indicated at 42. This shaft is mounted in an auxiliary frame 43 supported on the truss rods 12 and 13, and the shaft part 42 45 is rigidly connected to and adapted to rotate in unison with the barrel relatively to the other part which is held against such rotation by a removable pin 44 passed through the frame, such last mentioned shaft part having 50 a squared end 45 by which the spring may be wound up. The outer end of the shaft part 42 is rotatively connected to an indicator 46 which is moved in unison with the carriage, through the spring barrel and indicates the 55 position of the carriage relatively to the divisions on the time sheet. These divisions on the embodiment illustrated consist of columns representing the days of the week, and sub-divisions of each column representing 60 the working periods of each day, the equivalent graduations appearing on the indicator dial.

- The means for moving the carriage towards the drum or platen in the printing operation consists of a push-rod 50 extending

through the drum shaft 17 and in operative engagement at its front end with lever 4 and at its rear end with one arm of a bell-crank lever 51 pivoted on the frame as at 52, the other arm of the lever being connected to the carriage suspension rod 29 through link 53. The length of this link is adjustable so that the vertical movement of the carriage may be varied when desired.

In order to yieldingly maintain the carriage in its normal raised position and to return it to this position upon completion of each printing operation a pair of tensional springs 54 and 55 located on opposite sides of the link are connected at their upper ends to 70 studs 56 on the rear end frame and at their lower ends to pin 57 pivotally connecting the link to lever 51.

To provide perfect freedom for the suspension rod and carriage in their vertical 75 unisonal movement and to ensure a uniform printing pressure of the type wheels on the time sheet throughout the length thereof the suspension rod has mounted thereon adjacent its ends rollers 60 and pinions 61, and 80 fixed vertical guides 62 and racks 63 are mounted on the end frames on opposite sides of the rod, the rollers bearing against the guides and the pinions intermeshing with the racks. One of these racks may be adjusted 85 vertically through screws 65 and 66 to vary printing pressure as desired thereby 90 making it possible to obtain a uniform printing pressure irrespective of the position of the carriage.

100 The escapement mechanism which controls the intermittent feed of the carriage across the time sheet consists of a worm 70 mounted on the minute shaft 24 of the clock movement, a worm wheel 72 in intermeshing relation with the worm and keyed upon the lower end of a vertical shaft 73, a rotary escapement rack 74 keyed upon the upper end of such shaft, a toothed escapement wheel 75 rotatable on shaft 76 and in intermeshing 105 relation with the rack, a pulley 77 mounted on shaft 76 and rotatable in unison with said escapement wheel in a counterclockwise direction, or independently of the wheel in a clockwise direction, as viewed in Fig. 7, a ratchet wheel 78 rotatable in unison with the pulley on the same shaft, a pawl 78a carried by the escapement wheel and adapted 110 to engage the ratchet wheel, and metal tapes 79 and 80. Pulley 77 has two grooves and one end of tape 79 (see Fig. 9) is connected thereto in one groove as at 77a and its opposite end is connected to a pin 81 slidably mounted in the carriage frame and encircled by a spring 82 which permits of a slightly 115 rearward movement of the carriage relatively to the pulley for a purpose to be hereinafter explained. Tape 80 (see Fig. 10) is connected at one end to the pulley 77 in its other groove and extends upwardly over 120

pulley 83 and around pulley 84 and is connected at its opposite end to bracket 38 on the carriage. The circular teeth of the rack 74 correspond to the number of work periods 5 in each day and each tooth has a notch 85 located at a given point on its circumference through which the teeth of the escapement wheel may pass, consequently as the rack is rotated by the clock movement the 10 escapement wheel will be permitted to intermittently rotate as its teeth register with and pass through the notches. The teeth on the escapement wheel are so spaced apart that only one is in engagement with the 15 rack at a time, each tooth completing its intermittent travel along the rack before the next moves into rack engaging position. The ratchet and pawl connection between the escapement wheel and pulley 77 causes the 20 latter to rotate in unison with the former in a counterclockwise direction as hereinbefore mentioned but permits independent rotation of the pulley in the reverse direction, rotation of the escapement wheel in the last 25 mentioned direction being prevented by a segmental check plate 86 pivoted on the frame at 87 and yieldingly maintained in contact with a wheel 88 by a spring 89. The wheel 88 forms a part of a unit which is rotatably mounted upon a shaft 76 and which 30 is rotatively connected to the escapement wheel. This unit in addition to the wheel 88 comprises a cam 105 and a knurled wheel 106 of larger diameter located between and 35 uniting the cam and wheel 88, and the unit is rotatively connected to the escapement wheel by a substantially circular spring 107 one end of which is secured to the knurled wheel as at 107a and the opposite end to 40 a pin 108 on the near side of the escapement wheel. The function of this unit is to permit the carriage to be advanced relatively to the time sheet. When, for instance, it is desired to record in a different day column, 45 rotation of the knurled wheel 106 in a clockwise direction, as viewed in Fig. 7, moves pawl 78a clear of the ratchet tooth with which it is in engagement and allows the carriage to advance one day on the time 50 sheet. It should be noted here that the ratchet wheel 78 has only six teeth, each tooth representing one day so that where the pawl jumps one tooth the carriage advances one day on the time sheet. The pawl is moved 55 out of engagement with the ratchet wheel by the curved rise 109 in the cam engaging pin 110. This pin is mounted upon the pawl and projects through a slot 112 in the escapement wheel normally assuming the position 60 shown in Fig. 7. The turning movement of the cam relatively to the escapement wheel is limited by shoulders 113 and 114 constituted by a notch 115 in the cam in which pin 65 108 is located, the limit of the movement be-

ing reached when shoulder 114 engages the pin.

From the foregoing it will be noted that the carriage may be moved by hand in the reverse direction to its normal travel; or, on the other hand, may be advanced, the former movement being accomplished by manually pushing back the carriage along its suspension rod, and the latter by turning handwheel 106. It will be observed, however, that these manual movements cannot disturb the relationship between the time element, rack and escapement wheel. The importance of this feature lies in the fact that it is consequently impossible under normal conditions to disturb the relationship of the carriage to the time element in so far as the work periods are concerned thereby preventing much of the trouble experienced in the past with recorders of this type. To take care of abnormal conditions, for instance as when a workman has continued to work past the time at which the carriage is shifted into the next work period and wishes to record his stopping time in the preceding period, a push pin 90 (Figs. 1 and 10) is slidably mounted in the upper portion of the dial. This pin when pressed inwardly is adapted to engage one arm of a bell-crank lever 91 and raise the other arm of the latter and as this last-mentioned arm carries the pulley 83, a rearward pull is exerted on the carriage through tape 80 thereby moving the carriage back the required distance against the yielding resistance of spring 82. Pin 90 is held in its inward position until the punching operation has been completed and when it is released the carriage automatically returns to its normal position.

What is claimed is:

1. In a workman's time recorder, the combination with a platen adapted to carry a time sheet, a time mechanism, a carriage located adjacent the platen and movable longitudinally relatively thereto, carriage impelling means, printing mechanism, mounted upon the carriage and adapted to be moved into contact with the time sheet on the platen, and means operatively connecting the printing mechanism to the time mechanism; of an intermittently movable escapement means controlled by the time mechanism, carriage connecting means, and rotary means effecting an operative connection between the escapement means and carriage connecting means, said rotary means being constructed and arranged to cause the carriage to move intermittently in one longitudinal direction in unison with the intermittent movement of the escapement means, and permit movement of the carriage in the reverse longitudinal direction independently of said escapement means.

2. In a workman's time recorder, the combination with a platen adapted to carry a

- time sheet, a time mechanism, a carriage located adjacent the platen and movable longitudinally relatively thereto, carriage impelling means, printing mechanism mounted upon the carriage and adapted to be moved into contact with the time sheet on the platen, and means operatively connecting the printing mechanism to the time mechanism; of an intermittently movable escapement means controlled by the time mechanism, carriage connecting means, and rotary means effecting an operative connection between the escapement means and carriage connecting means, said rotary means being constructed and arranged to cause the carriage to move intermittently in one longitudinal direction in unison with the intermittent movement of the escapement means, and permit movement of the carriage in the reverse longitudinal direction independently of said escapement means, and manually operable means associated with said rotary means for releasing the carriage to permit it to move in the first-mentioned direction independently of the escapement means.
3. In a workman's time recorder, the combination with a platen adapted to carry a time sheet, a time mechanism, a carriage located adjacent the platen and movable longitudinally relatively thereto, carriage impelling means, printing mechanism mounted upon the carriage and adapted to be moved into contact with the time sheet on the platen, and means operatively connecting the printing mechanism to the time mechanism, of an escapement means controlled by the time mechanism and rotatable intermittently in one direction, means permitting said rotation of the escapement means but preventing rotation of the latter in the opposite direction, carriage connecting means and means effecting an operative connection between the escapement means and carriage connecting means, the last said connecting means being constructed and arranged to cause the carriage to move intermittently in one longitudinal direction in unison with the intermittent rotation of the escapement means and permit movement of the carriage in the reverse longitudinal direction independently of the escapement means.
4. In a workman's time recorder, the combination with a time mechanism, a carriage, carriage impelling means and printing mechanism mounted upon the carriage and controlled by the time mechanism, of means controlled by the time mechanism for intermittently moving the carriage in one direction, said means consisting of an intermittently rotatable escapement wheel having a predetermined number of spaced teeth on its periphery, a pulley operatively connected to the carriage, ratchet and pawl mechanism connecting the wheel and pulley and causing the pulley to move intermittently in unison with the escapement wheel and permitting independent rotation of the pulley in the reverse direction, means preventing rotation of the escapement wheel in said reverse direction, and a rotary rack in intermeshing relationship with said escapement wheel and controlling its intermittent rotation, said rack being controlled by the time mechanism and having a predetermined number of spaced circular teeth and each tooth being notched to permit intermittent rotation of the escapement wheel.
5. In a workman's time recorder, the combination with a time mechanism, a carriage, carriage impelling means, and printing mechanism mounted upon the carriage and controlled by the time mechanism, of means controlled by the time mechanism for intermittently moving the carriage in one direction, said means consisting of an intermittently rotatable escapement wheel having a predetermined number of spaced teeth on its periphery, means operatively connecting the escapement wheel to the carriage, said last-mentioned means being constructed and arranged to allow the carriage to move intermittently in one direction in unison with the intermittent movement of the escapement wheel and to permit movement of the carriage in the opposite direction independently of the escapement wheel, and a rotary rack in intermeshing relationship with said escapement wheel and controlling its intermittent rotation, said rack having a predetermined number of spaced circular teeth and each tooth being notched to permit intermittent rotation of the escapement wheel.
6. In a workman's time recorder, the combination with a clock mechanism including a minute shaft and an intermittently movable carriage, of escapement mechanism controlling the intermittent movement of the carriage, said escapement mechanism consisting of a second shaft, a rotative connection between said shafts consisting of a worm and worm wheel respectively keyed on said shafts, a rack on said second shaft and rotatable therewith, said rack having a predetermined number of spaced circular teeth and each tooth having a radially disposed notch at a given point in its circumference, an intermittently rotatable escapement wheel controlled by said rack, said wheel having a predetermined number of teeth adapted to intermesh with the rack and intermittently pass through the said notches therein, and means connecting the escapement wheel to the carriage for causing the latter to move intermittently in unison with said wheel.
7. In a workman's time recorder, the combination with a time mechanism, and a carriage; of an escapement mechanism controlled by the time mechanism and in turn controlling the carriage and permitting it to move intermittently, said escapement mechanism

consisting of a rotary rack rotatively connected to the time mechanism and having notched circular teeth, an escapement wheel having spaced teeth adapted to successively intermesh with the teeth of the rack, said rack permitting intermittent rotation of the escapement wheel in one direction, and extraneous means preventing rotation of the escapement wheel in the reverse direction.

8. In a workman's time recorder, the combination with a time mechanism, and a carriage; of an escapement mechanism controlled by the time mechanism and in turn controlling the carriage and permitting it to move intermittently, said escapement mechanism consisting of a rotary rack rotatively connected to the time mechanism and having notched circular teeth, an escapement wheel having spaced teeth adapted to successively intermesh with the teeth of the rack, said rack permitting rotation of the escapement wheel in one direction, and means preventing rotation of the escapement wheel in the reverse direction, consisting of a second wheel rotatable in unison with the escapement wheel and a check device in operative engagement with the second wheel and adapted to permit rotation of the second wheel in one direction but prevent rotation in the reverse direction.

9. In a workman's time recorder, the combination with a platen adapted to carry a time sheet, a time mechanism, a carriage located adjacent the platen, and movable longitudinally relatively thereto, carriage impelling means, type wheels mounted upon the carriage and adapted to be moved into contact with the time sheet on the platen, and means operatively connecting the type wheels to the time mechanism; of an intermittently movable escapement means controlled by the time mechanism, and means effecting an operative connection between the escapement means and carriage, said connecting means being constructed and arranged to cause the carriage to move intermittently in one longitudinal direction in unison with the intermittent movement of the escapement means and permit movement of the carriage in the reverse longitudinal direction independently of said escapement means, and means under the control of a workman for moving the carriage in said reverse longitudinal direction independently of the escapement means.

10. In a workman's time recorder, the combination with a platen adapted to carry a time sheet, a time mechanism, a carriage located adjacent the platen, and movable longitudinally relatively thereto, carriage impelling means, type wheels mounted upon the carriage and adapted to be moved into contact with the time sheet on the platen, and means operatively connecting the type wheels to the time mechanism; of an intermittently movable escapement means controlled by the

time mechanism, and means effecting an operative connection between the escapement means and carriage, said connecting means having provisions to cause the carriage to move intermittently in one longitudinal direction in unison with the intermittent movement of the escapement means and having provisions to permit movement of the carriage in the reverse longitudinal direction independently of said escapement means and means under the control of a workman for moving the carriage in said reverse longitudinal direction independently of the escapement means, and manually operable means for rendering the latching action of the escapement ineffective to permit the carriage to move in the first-mentioned direction independently of the escapement means.

11. In a workman's time recorder, the combination with a platen bearing a time sheet, a carriage located adjacent the platen and movable across the time sheet, time controlled means for intermittently moving the carriage in one longitudinal direction relatively to the platen, a yielding connection between said last-mentioned means and the carriage permitting limited longitudinal movement of the latter in the reverse direction, printing mechanism carried by the carriage and movable into engagement with the time sheet, a metal tape connected to the carriage, and means under the control of a workman for exerting sufficient tension on said tape to move said carriage in said reverse longitudinal direction.

12. In a workman's time recorder, the combination with a platen adapted to carry a time sheet, a carriage, and printing mechanism mounted upon the carriage; of means located above the platen and extending parallel to the axis of the same and having the carriage suspended therefrom, the carriage being slidable along said means in parallelism with the platen, means under the control of a workman for moving said carriage suspension means and carriage vertically in unison relatively to the platen, and timing mechanism for intermittently moving the carriage along said carriage suspension means.

13. In a workman's time recorder, the combination with the frame thereof, a platen adapted to carry a time sheet, a carriage, and printing mechanism upon the carriage; of a suspension rod located above the platen and extending parallel to the axis of the same, a sleeve slidable longitudinally upon the suspension rod, said sleeve having the upper end of the carriage rigidly connected thereto and movable therewith, timing mechanism for moving the carriage and sleeve along said rod in one direction, means supporting the suspension rod at its ends consisting of racks mounted upon the frame and pinions carried by the ends of the rod and intermeshing with the racks, means yieldingly main-

taining the rod in its uppermost position, and means under the control of a workman for moving the rod and carriage in unison downwardly towards the platen.

14. In a workman's time recorder, the combination with the frame thereof, a hollow shaft horizontally mounted in the frame, a platen mounted on said shaft, a time-controlled carriage movable intermittently in a longitudinal direction relatively to the platen, means supporting the carriage above the platen and movable vertically in unison with the carriage relatively to the platen, a push rod extending completely through said hollow shaft and movable longitudinally therein, manually operable means under the control of a workman for moving said push rod longitudinally, and means operatively connecting the push rod to the carriage supporting means whereby the latter is moved vertically when the push rod is moved longitudinally.

15. In a workman's time recorder, the combination with the frame thereof, a hollow shaft mounted in the frame, a platen mounted on said shaft, a time-controlled carriage movable intermittently in a longitudinal direction relatively to the platen, means supporting the carriage above the platen and movable vertically in unison with the carriage relatively to the platen, a push rod extending completely through said hollow shaft and movable longitudinally therein, manually operable means under the control of a workman for moving said push rod longitudinally, an adjustable link connected at its upper end to the carriage supporting means, a bell-crank lever pivoted in the frame and having one arm operatively connected to the lower end of the link and the other arm in engagement with the push rod whereby longitudinal movement of the push rod in one direction moves the said carriage towards the platen, and means for yieldingly maintaining the carriage supporting means in raised position.

16. In a workman's time recorder, the combination with a platen adapted to carry a time sheet, and a time-controlled carriage movable longitudinally and vertically relatively to the platen; of means for supporting the carriage in position above the platen, said means being constructed and arranged to permit said longitudinal movement of the carriage and being movable vertically in unison with the carriage, and means for guiding the said carriage supporting means in its vertical movement.

17. In a workman's time recorder, the combination with the frame thereof, a platen adapted to carry a time sheet, and a time-controlled carriage movable longitudinally and vertically relatively to the platen; of means for supporting the carriage in position above the platen, said means being con-

structed and arranged to permit said longitudinal movement of the carriage and being movable vertically in unison with the carriage, vertical guides upon the frame, rollers mounted on said carriage supporting means and movable vertically on said guides, and means under the control of a workman for moving the carriage supporting means vertically on the guides towards the platen.

18. A workman's time recorder provided with a time-controlled carriage movable intermittently in a longitudinal direction and printing mechanism on the carriage, characterized by a platen located beneath the carriage, and a shaft rotatably carrying the platen; of means for rotatably supporting said shaft in any one of a plurality of different axial positions relatively to the carriage to accommodate platens of different diameters.

19. In a workman's time recorder, the combination with printing mechanism, of a platen supporting element, a support for said element and means for adjustably attaching said element to said support to permit adjustment relatively to the printing mechanism to accommodate platens of different diameters.

20. In a workman's time recorder, the combination of a platen, a shaft supporting said platen, and end frames for supporting the shaft in any one of a plurality of vertically spaced positions, substantially as described.

21. In a workman's time recorder, the combination with spaced vertical end frames having openings therein, horizontally spaced parallel truss rods extending between the end frames and having their ends passed through the said openings, means for adjustably securing the rods in the end frames; of a horizontal suspension rod disposed parallel to the truss rods and supported at its ends in the end frames and movable vertically thereon, a sleeve slidable longitudinally upon the suspension rod, a carriage rigidly suspended at its upper end from said sleeve and movable vertically with the suspension rod and longitudinally with the sleeve, the lower portion of the carriage extending between the said truss rods, and means on the carriage at opposite sides thereof in constant bearing relation with said last-mentioned rods irrespective of the position of the carriage.

22. In a workman's time recorder, the combination with a carriage; of means inducing movement of the carriage in a longitudinal direction, said means consisting of a two-part shaft, a spring barrel on said shaft and rotatable in unison with one shaft part relatively to the other part, means normally preventing rotation of the last mentioned shaft part, a spiral spring within the barrel and having its ends respectively connected to the last mentioned shaft part and the barrel, and a rotary indicator rotatably connected to the first-mentioned shaft part, the timing mecha-

nism controlling movement of the carriage in said longitudinal direction.

23. In a workman's time recorder, escapement mechanism consisting of a rotary escapement wheel having a series of spaced teeth projecting radially from its periphery, and a rotary rack in intermeshing relation with the wheel, said rack rotating on an axis at right angles to the axis of the escapement wheel and having circular teeth all of which are located at a uniform distance from the axis of the escapement wheel.

24. In a workman's time recorder, the combination with a time mechanism, and an intermittently movable carriage; of escapement mechanism controlling the intermittent movement of the carriage, said escapement mechanism consisting of an intermittently rotatable escapement wheel having a predetermined number of spaced radially disposed teeth, and a rotary rack rotatively controlled by the time mechanism and having a predetermined number of spaced circular teeth in intermeshing relationship with the teeth of the wheel, each tooth of the rack having a radially disposed notch at a given point in its circumference and said teeth of the rack being arranged in an arc concentric to the axis of the escapement wheel, and means connecting the escapement wheel to the carriage for causing the latter to move intermittently in unison with said wheel.

25. In a workman's time recorder, the combination with a time mechanism, and a carriage; of an escapement mechanism controlled by the time mechanism and in turn controlling the carriage and permitting it to move intermittently, said escapement mechanism consisting of a rotary rack rotatively connected to the time mechanism and having notched circular teeth, an escapement wheel having spaced teeth adapted to successively intermesh with the teeth of the rack, said rack permitting intermittent rotation of the escapement wheel in one direction, and extraneous means preventing rotation of the escapement wheel in the reverse direction.

26. A workman's time recorder having spaced end frames, a time controlled carriage and printing mechanism on the carriage characterized by a platen supporting shaft extending between the end frames and a plurality of separate and distinct bearings for said shaft in one end frame, and an adjustable shaft bearing in the other end frame, said bearings being adapted to support said shaft in a plurality of different positions to accommodate platens of different diameters.

27. In a workman's time recorder, an escapement mechanism consisting of an escapement wheel having a series of spaced teeth projecting radially from its periphery and a rotary rack having a profile concentric to the axis of the wheel and in intermeshing relationship therewith, said rack comprising

a series of spaced notched circular teeth collectively being progressively reduced in diameter from the ends of the rack towards the middle thereof.

In testimony whereof I hereto affix my signature.

GEORGE R. WOOD.
